CLAIM

The ornamental design for a shopping basket, as shown and described.

DESCRIPTION

FIG. 1 is an upper left perspective view of a shopping basket showing my new design;

FIG. 2 is a lower left front side perspective view thereof, the lower right rear perspective view being a mirror image thereof;

FIG. 3 is a top plan view thereof;

FIG. 4 is a front elevation view thereof, the rear side being a mirror image thereof; and,

FIG. 5 is a left side elevation view thereof; the right side being a mirror image thereof.
